(57) **CLAIM**

The ornamental design for a flotation aid, as shown and described.

DESCRIPTION

FIG. 1 is perspective view of a flotation aid, showing our design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is a right side view thereof, showing the flotation aid in an alternate orientation.

The broken lines depict portions of the article that form no part of the claimed design.
